STERILIZER CONSTRUCTION

Raymond L. Jewell, Erie, Pa., assignor to
American Sterilizer Company, Erie, Pa.

Application November 14, 1944, Serial No. 563,365

4 Claims. (Cl. 220—10)

1

This invention relates to pressure sterilizers, and more particularly to the body and door construction thereof, together with the manner of assembling the several parts of the sterilizer.

An object of the invention is found in the novel manner of forming the front edge of the sterilizer or body, which cooperates with the locking bars of the sterilizer closure.

Another object of the invention resides in the manner of attaching the inner and outer concentrically arranged sheets which form the sterilizer body, whereby they are readily attached to the door holding ring or locking edge so that a pressure-tight joint is formed without unsightly welds showing from the exterior of the sterilizer, and to do away with the conventional cast ring which heretofore has formed the locking means for the doors.

In the accompanying drawings, the figure is a vertical longitudinal section of one form of the sterilizer showing the improved door construction and the manner of welding and concentric body plates and rear plate.

Specifically in the drawings, 1 and 3 denote spaced concentric walls which may be cylindrical or in the form of a square with rounded edges. These horizontally arranged spaced walls or sheets define the inner boiler or annular steam jacket of this type of an autoclave sterilizer, and insofar as the spacing of the sheets, together with an end frame 5 and rear sheet 7, is concerned, is conventional. The term "annular" as used herein with respect to the steam jacket is to be taken in its broad sense of ring-shaped, and therefore includes the space defined by body sheets or walls 1 and 3 of generally rectangular cross-section as well as those which are circular. The novelty of this invention includes the manner of fabricating the sterilizer walls 1 and 3 and the front end frame or ring 5 and the rear sheet or plate 7, together with the improved construction of the pressure door frame and the manner of welding these units into an integral sterilizer structure. In the prior art sheets such as 1 and 3 have customarily been riveted to the inner and outer surfaces of a ring member, which is usually cast and therefore, necessarily, considerable machining is required. This ring member is provided with a larger diameter integrally formed and spaced flange for holding the ends of door locking bars, such as 9, rocking eccentrically and outwardly over a cam surface, such as 11, formed on the door closure 13. Also in the prior art the projected and movable closure arms 9 bind against the interior of the outer flange of the en-

2

larged diameter spaced flange on the sheet ring, as before described, to press the door closure tight against the front surface of the end ring member, which normally is recessed for the purpose of holding a gasket, and cooperates with a flange formed on the door closure for obtaining a tight seal. This prior construction is open to a number of objections, due mainly to the poor joint secured by the riveting of the body members 1 and 3 on the inner and outer sides of the annular flange of the end frame and the cost of the cast end frame, which must be machined to very close tolerances, in addition to the massiveness of the construction of such end frame or ring.

15 In the present instance the end frame or ring 5 takes the form of a simple rolled, continuous flanged member having an inturned rear edge 15 forming the surface to which the sterilizer wall sheets 1 and 3 are attached. The forward spaced 20 inturned edge 17 is of comparatively short length as compared to the elongated rear edge 15 to provide the necessary clearance for the manually projected locking arms 9. These arms, when the door 13 is pivoted against the outer surface of 25 the downturned flange 15, are moved eccentrically and outwardly by the hand wheel 19 and associated mechanism indicated by numeral 21. As this precise door bar projecting arrangement does not form a part of the invention, it is sufficient to say when the door 13 is closed, hand wheel 19 is operated and through the associated mechanism the outer ends of arms 9 are projected radially under the front downturned flange 17 of the end frame member 5, and, thereafter, 30 the inner ends of the arms are moved inwardly so that they fulcrum over the surfaces 11 and press the packing or gasket 23 positioned in a recess 25 on the inner face of the door against the outer surface of the inturned flange 15. Sufficient pressure can be created in this manner to 35 seal the door 13 and effectively prevent leakage from the inner sterilizing chamber 27.

As before stated the end ring or frame member 5 may be readily fabricated, as by rolling from 45 any suitable material. Preferably the ring is formed of malleable Monel metal, but such a ring or rounded corner, square configuration can be rolled or formed and does not have to be machined to any extent.

50 In fabricating a sterilizer body of the type herein disclosed, the inner sheet 3 defining the sterilizer space 27 is of an internal size substantially that of the diameter of the opening 29 of the ring member 5, and its elongated flange 15 and the 55 shaped sheet 3 are welded at 31 on the exterior

of the sheet at the point of juncture of the sheet end and flange 15. The second step of fabrication comprises placing the head or end plate 7 against the opposite end of the body sheet 3 and welding the same at its point of juncture 33 with the end sheet, which as shown is less than the diameter of the head 7 as the sheet extends radially to the outer sheet 1. After this preliminary fabrication is accomplished the outer formed sheet 1 is then placed over the end plate 7 and pressed forwardly until its forward edge abuts the flange 15 of the end ring 5, whereupon it is peripherally welded thereto at 35. It is obvious that the diameter of the head 7 permits the ready placing of the formed sheet 1 thereover and maintains the same in proper spaced relation to the inner formed sheet 3. The outer sheet is thereafter peripherally welded at its point of contact 37 with the peripheral edge of the head 7. Preferably a layer of insulation 39 is laid over the outer sheet 1 and a sheet metal covering sheet 41 placed over the insulation to hold it in place and to present a pleasing appearance and readily cleanable exterior.

I claim:

1. In a sterilizer, the combination comprising a continuous metal door frame having an approximately U-shaped cross section with parallel, inwardly directed long and short legs; a spaced pair of metal body sheets defining a steam jacket and a sterilizing chamber; closure means for the sterilizing chamber and the steam jacket fixedly secured to the body sheets at one end of the sterilizer, said body sheets at the other end of the sterilizer being arranged with their entire corresponding ends continuously abutting the outer face of the long leg of said door frame; and continuous welding seals extending around the respective ends of the body sheets and securing said sheets to the outer face of the long leg of said door frame.

2. In a sterilizer, the combination comprising a continuous metal door frame having an approximately U-shaped cross section with parallel, inwardly directed long and short legs of uniform thickness; a spaced pair of concentric metal body sheets defining an annular steam jacket and a sterilizing chamber; closure means for the sterilizing chamber and the steam jacket fixedly secured to the body sheets at one end of the sterilizer, said body sheets at the other end of the sterilizer being arranged with their corresponding ends continuously abutting the outer face of the long leg of said door frame and with the inside of the inner sheet and the inner peripheral surface defined by said long leg being formed and arranged as smooth continuations of each other; continuous welding seals extending on the respective outsides of the body sheets and securing said sheets to the outer face of the long leg of said door frame; an insulating layer covering the outside body sheet; and a sheet metal layer extending over the insulating layer and the welding seal for the outside body sheet.

3. A sterilizer comprising a spaced pair of metal body sheets constructed and arranged to

form a steam jacket; a continuous door frame having an approximately U-shaped cross section with inwardly directed long and short legs, said body sheets being arranged with their corresponding ends continuously abutting the outer face of the long leg of said door frame and with the inside of the inner sheet and the inner peripheral surface defined by said long leg being formed and arranged as smooth continuations of each other; continuous sealing joints extending only on the respective outsides of the body sheets and securing said sheets to the outer face of the long leg of said door frame; a removable door formed and arranged for closing engagement with the inner face of the long leg of said door frame; door locking means having relatively movable portions adapted to engage the inner face of the short leg of said door frame; and means constructed and arranged to close the sterilizer and steam jacket at the opposite ends of said body sheets.

4. A sterilizer comprising a concentric pair of metal body sheets constructed and arranged to form an annular steam jacket; a continuous metal door frame formed of malleable metal of uniform thickness and having an approximately U-shaped cross-section with inwardly directed long and short legs, said body sheets being arranged with their corresponding ends continuously abutting the outer face of the long leg of said door frame and with the inside of the inner sheet and the inner peripheral surface defined by said long leg being formed and arranged as smooth continuations of each other; continuous welded sealing joints extending only on the respective outsides of the body sheets and securing said sheets to the outer face of the long leg of said door frame; a removable door formed and arranged for closing engagement with the inner face of the long leg of said door frame; door locking means mounted on said door and having relatively movable portions adapted to engage the inner face of the short leg of said door frame and the outer side of said door; and means constructed and arranged to close the sterilizer and steam jacket at the opposite ends of said body sheets.
